UNITED STATES PATENT OFFICE.

HENRY W. FISHEL, OF NEW YORK, N. Y.

BOUTONNIÈRE.

SPECIFICATION forming part of Letters Patent No. 500,195, dated June 27, 1893.

Application filed February 20, 1893. Serial No. 462,991. (No model.)

To all whom it may concern:

Be it known that I, HENRY W. FISHEL, of New York, county and State of New York, have invented a new and useful Improvement 5 in Boutonnières, of which the following is a specification.

This invention relates to boutonnières or buttonhole bouquets, the object being to produce a simple device having an artificial 10 flower adapted to be easily attached or detached from the buttonhole of a garment.

I will describe a device embodying my improvement and then point out the novel features in the claims.

15 In the accompanying drawings, Figure 1 is a perspective view of a boutonnière embodying my improvement. Fig. 2 is a partial section thereof. Fig. 3 is a section similar to Fig. 2 but showing a modification.

20 In both the examples of my improvement the flower is removably secured to the stud portion.

Referring by letter to the drawings A designates the post of a stud and A' the shoe or 25 back plate thereof, and A² shows a flower detachably secured to the stud. The flower consists of any suitable material, such as celluloid or porcelain.

In the example shown in Figs. 1 and 2, the 30 post A has an exterior thread a adapted to engage with a nut a' secured within the flower.

In Fig. 3 the post A is shown as tubular and having an interior thread with which a

threaded stem a² extended from the base of 35 the flower engages. This threaded stem may have a head a³ secured within the flower.

Having described my invention, what I claim is—

1. In a boutonnière, the combination with 40 an artificial flower, of a screw-threaded piece secured within the flower, and an externally-projecting screw-threaded post or shank engaging therewith, substantially as set forth.

2. In a boutonnière, the combination with 45 an artificial flower, of a screw-threaded piece secured within the flower, and a post or shank threaded toward its inner end and engaging with said other threaded piece and having a shoe or plate at its outer end, substantially 50 as set forth.

3. A boutonnière comprising an artificial flower, a threaded stem secured at its head within the flower and projecting from the base thereof, and an internally-threaded post or 55 shank one end of which engages said stem and having at its other end a shoe or plate adapted to be passed through a button-hole and to retain said post or shank therein, substantially as set forth. 60

In testimony whereof I have signed my name to this specification in the presence of two subscribing witnesses.

HENRY W. FISHEL.
